AMUSEMENT APPARATUS

Myer Gensburg, Chicago, Ill.

Application October 11, 1935, Serial No. 44,488

6 Claims. (Cl. 271—24)

This invention relates to an amusement apparatus and has for its principal object the provision of a novel combination and arrangement of parts which will be highly efficient in use and 5 inexpensive in construction.

Another object of this invention is to provide a novel device for dispensing a ticket or a portion of an indicia-bearing web, redeemable in merchandise prizes or the like, from a coin controlled amusement apparatus, of the so-called pin and marble game type, upon operation of the coin 10 slide.

Another object of the invention is to provide, in a coin controlled amusement game apparatus 15 of the so-called pin and marble game type, a novel device, coacting with and operable by movement of the ball-retaining member, for advancing the free end portion of a web of indicia-bearing tickets or the like through a dispensing outlet exteriorly of the cabinet to the player.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary top plan view of an amusement apparatus embodying a preferred form of the present invention;

Fig. 2 is a longitudinal sectional view taken substantially on line 2—2 in Fig. 1;

Fig. 3 is a fragmentary sectional detail view taken along line 3—3 in Fig. 1;

Fig. 4 is a fragmentary cross sectional detail view taken along line 4—4 in Fig. 3;

Fig. 5 is a sectional detail view on line 5—5 in Fig. 4;

Fig. 6 is a sectional detail view taken along line 6—6 in Fig. 4;

Fig. 7 is a fragmentary elevational view taken along line 7—7 in Fig. 4; and

Fig. 8 is a fragmentary sectional detail view taken along line 8—8 in Fig. 3.

Referring to the drawings, in which a preferred form of the present invention is illustrated, the reference numeral 10 indicates generally an amusement device which comprises a cabinet 11 including a member 12 which provides an inclined playing surface over which balls are adapted to be propelled by means of a plunger or the like 13.

The playing surface 12 includes ball-receiving openings or pockets 14 in which balls may be received or pocketed by means of a ball-retain-

ing member or slide panel 15 which is mounted in the cabinet 11 below the inclined playing surface 12 for movement parallel thereto, and is normally urged into the position as seen in Figs. 2 and 3 by a resetting spring 60. The ball-retaining member or slide panel 15 has a depending extension 16 at its lower end, and this extension 16 is engageable with the inner end portion (Fig. 2) of a coin slide 17 which is mounted in the front wall 18 of the cabinet 11. 10

Provided in the ball-retaining member or slide panel 15 are ball-receiving openings 19 which are normally disposed out of vertical alignment or registration with the pockets or ball-receiving openings 14, in the inclined playing board 12, 15 the openings 19 in the slide panel 15 being moved into vertical alignment or registration with the openings 14 in the inclined playing board 12 upon movement of the coin slide 17 (from left to right, Fig. 2).

Fastened to the lower end of the ball-retaining member 15 is a member 20 (Fig. 3) which has spaced depending extensions 21 and 22 (Fig. 3), and arranged between the depending extensions 21 and 22 is a pin 23 which is attached to and 25 projects laterally from a member 24. This member 24 is pivotally mounted between its ends, as at 26, upon a supporting member 25 which is arranged in the cabinet 11, and formed in the lower end portion of the member 24 is a slot 27. 30

Projecting into this slot 27 is a pin 28 which is carried by and projects laterally from a carriage 34 which is loosely mounted upon or floats upon a horizontal shaft 29. This carriage 34 is normally disposed in the position indicated at 35 "A" (Fig. 5).

A web-advancing roll 31 is mounted upon and fixed to the horizontal shaft 29, and is provided on its peripheral surface with a plurality of lugs 32, these lugs 32 being engageable in corresponding perforations which are formed in a web 33; the web-advancing roll 31 being formed as a part of a ticket dispensing device, which is generally indicated at 30.

Pivotedly mounted upon the member 34, as at 35, is a cam 36, and likewise mounted, as at 37, upon the member 34 is a spring 38 which tends to hold the cam 36 in its normal position (position "A", Fig. 5). Arranged upon the side wall of the web-advancing roll 31 are small extensions 40 or lugs 39, and these extensions 39 are arranged to correspond with the positions or spacings of the lugs 32 on the web-advancing roll 31.

Having a portion 62 which is slidably mounted below the web-advancing roll 31 (Fig. 8), in a 55

vertically extending slot 43 which is formed in the supporting member 25, and upon the same center line as the shaft 29, is a member 63 which includes two disc-like or cylindrical portions 40 and 41 (Figs. 4, 5, 6, and 8), the diameter of the disc-like portion 41 being slightly larger than that of the disc-like portion 40. The member 63—40—41 has a recess 42 formed therein, and the extensions or lugs 39 are engageable in this recess 42. It is to be noted that when the member 63 is in normal position (full lines, Fig. 5), the web-advancing roll 31 is latched against movement by the engagement of the lug 39 with the recess 42.

15 A member 44 is pivotally mounted in the cabinet 11 upon a supporting wall 45, as at 46 (Fig. 7), and this member 44 normally bears upon the web 33. Formed as an integral part of the member 44 is an arm 47, and attached to the member 20 44 is a link or rod 48, this link 48 being in turn attached to an indicator 49 which is pivotally mounted, as at 50, upon the top wall of the cabinet 11.

Operation

25 When the coin slide 17 is moved (from left to right, Fig. 2), the inner end portion of the same engages the depending extension 16 of the ball-retaining member 15, thereby moving the ball-retaining member 15 (left to right, Fig. 2) so as to liberate any balls which may be disposed in the ball-receiving pockets 14, this movement of the ball-retaining member 15 moving the ball-receiving openings 19 into registration with the ball openings or pockets 14 in the inclined playing board 12, and the spent balls thus falling by gravity upon the inclined ball return runway 51.

30 The foregoing movement of the ball-retaining member 15 (left to right, Figs. 2 and 3) also causes 40 the member 28 which is mounted thereon to move (left to right, Figs. 3, 6 and 7), so that the angled portion 22 will engage the pin 23 which extends laterally from the member 24, thereby pivoting the member 24 (counterclockwise, from full to 45 dotted line position, Fig. 3), this movement of the member 24 being limited by means of the pin 28 which works in the slot 52 (Fig. 3).

35 As the member 24 is thus pivoted (from full to dotted line position, Fig. 3), the pin 28 is 50 moved (from left to right, Fig. 3) in the slot 52, thereby moving the member 34 which carries the pin 28 from position "A" through position "B" (Fig. 5). This movement of the member 34 in turn causes the cam 36 to ride over the peripheral 55 surface 41 of the member 63 and thus forces the member 63 to move downwardly in the slot 43 out of engagement with the horizontal extension 39 of the web-advancing roll 31. During this movement the cam 36 engages the horizontal extension 39 of the web-advancing roll 31, whereupon further movement of the member 34 (in a 60 counterclockwise direction, Fig. 5) causes the web-advancing roll 31 to move therewith in the same direction, thus advancing the web 33 a pre-determined distance, the extreme position of the member 34 being indicated at "C" (Fig. 5). During this operation the web 33 is guided onto the web-advancing roll 31 by means of a guideway 53 (Fig. 5), and the web 33 is guided along the 65 peripheral surface of the web-advancing roll 31 by means of a guide 55 which communicates with a guideway 56 through which the free end portion of the web 33 is forced.

70 Arranged in the cabinet 11 immediately above 75 the guideway 56 is a member 57 which has a

reduced upper end portion 58 which is engageable in the perforations which are formed in the web 33, the free end portion of the web 33 being forced through the dispensing outlet 59 in the cabinet 11 so that it may be readily severed by the operator of the device.

When the ball-retaining member is returned to its initial position (right to left, Fig. 2; left to right, Fig. 3) by action of its resetting spring 60, the depending extension 21 thereof engages the pin 23 which is carried by the member 24, and thereby pivots the latter back into its initial position (clockwise into full line position, Fig. 3).

After the member 34 has moved from position "B" to position "C" (Fig. 5), the member 63 is returned to its initial position by means of resetting spring 61 (Fig. 6), whereupon the cam 36 passes over the member 63 and, upon coming into contact with the member 63 assumes the position indicated at "D" (Fig. 6). Thereupon, after passing over the member 63, the cam 36 assumes its original position, indicated at "E" (Fig. 6) and "A" (Fig. 5). During this operation the spring 38 acts as a lever and forces the cam 36 back into its initial position.

25 The present apparatus includes a device for enabling the player thereof to determine, without dismantling the apparatus, when a web of tickets therein has been used. To this end there is pivotally mounted in the cabinet 11 upon the supporting wall 45 a finger 44, this finger 44 resting upon the web 33 until the web has been used up or exhausted, whereupon the finger 44 will pivot (counterclockwise, Fig. 3; clockwise, Fig. 7), this pivoted movement of the finger 44 causing the arm 47, link 48, and indicator 49 to move (from full to dotted line position, Fig. 7), and thus indicating that the web 33 has been used up or exhausted.

40 While I have illustrated and described the preferred form of construction for carrying my invention into effect, this is capable of variation and modification without departing from the spirit of the invention. I, therefore, do not wish to be limited to the precise details of construction set 45 forth, but desire to avail myself of such variations and modifications as come within the scope of the appended claims.

Having thus described my invention, what I claim as new and desire to protect by Letters 50 Patent is:

1. A ticket feed device for game apparatus having a ticket aperture and a game-reset mechanism, comprising, with a support: a rotatable feed drum having spaced lugs extended in an axial direction therefrom; a drum advancing member mounted co-axially with said drum and having a driving and release cam adjacent an edge thereof for driving engagement with the said lugs on said drum; a movement-limiting member having a cam-surface and a stop formation and mounted for movement in a direction away from the periphery of said drum by engagement with the driving and release cam on said advancing member, and having means urging it into engagement with a said lug on said drum; and means guiding a ticket web from said drum relative to a said ticket aperture, and means operable by said game-resetting mechanism for moving said advancing member. 60

2. An indicating ticket feed device for game apparatus having a game operating member, comprising: a supporting frame having ticket web guides; a rotatable web feeding drum having stop members; a drum-advancing member sup- 70

- ported for co-axial movement with said drum and having a driving cam positioned for engagement with said stop members on said drum when said advancing member is operated; a drum-stop 5 latch supported on said frame for reciprocal movement radially of said drum and having a part engageable with a drum-stop member and a surface for cammed engagement with said driving cam on said advancing member; means normally 10 positioning said stop latch into stopping engagement with said drum stop members; indicating means for said drum comprising a finger adapted to ride against the said drum and webbing carried thereby, and pivoted for movement 15 radially thereto responsive to changing aggregate diameter of webbing and drum to position an indicator in said game apparatus; and means operatively connecting said game operating member and said drum advancing member.
- 20 3. An indicating ticket feed device for game apparatus of the type having a game-operating member, comprising: a rotatable ticket-web feed with stop parts engageable with a movement limiting stop member; a web-feed driving member 25 movable co-axially with said web feed and having a drive part for transient engagement with said web feed and the aforesaid stop parts thereon; a movement limiting stop member supported for movement radially of said web feed and having 30 a cam face terminating in an abutment and means urging it toward said web feed whereby to position said abutment in stopping position before the said stop parts on said web feed; the aforesaid limiting stop member being movable 35 away from said web feed by camming engagement with the said drive part on the said web feed advancing member whereby the said abutment is withdrawn from stopping position as aforesaid, to permit the movement of said web feed with said advancing member; means supporting the aforesaid parts in operative engagement, means operatively connecting a said game operating member with the said web advancing member, and indicating means with said game 40 apparatus co-operable with said web feed to indicate the substantial exhaustion of ticket webbing therein.
- 45 4. In a game apparatus having a game operating member, a ticket web feed mechanism comprising: a rotatable web feeding drum, a locking member movable radially of said drum to prevent rotation of the latter, a drum-rotating member pivotable co-axially therewith and having a part transiently engageable with the said drum to 5 rotate the same in advancing movement and engageable with the said locking member to move the latter radially out of locking position to permit movement of the drum, together with means operatively connecting said game operating 10 member with said drum rotating member.
5. A ticket feed device comprising, with a support: a rotatable feed drum having spaced lugs extended in an axial direction therefrom; a drum advancing member mounted co-axially with said drum and having a driving and release cam adjacent an edge thereof for driving engagement with the said lugs on said drum; a movement-limiting member having a cam-surface and a stop formation and mounted for movement in a 20 direction away from the periphery of said drum by engagement with the driving and release cam on said advancing member, and having means urging it into engagement with a said lug on said drum and means for guiding a ticket web 25 away from said drum.
6. An indicating ticket feed device comprising a supporting frame having ticket web guides; a rotatable web feeding drum having stop members; a drum-advancing member supported for co-axial 30 movement with said drum and having a driving cam positioned for engagement with said stop members on said drum when said advancing member is operated; a drum-stop latch supported on said frame for reciprocal movement radially of said drum and having a part engageable with a drum-stop member and a surface for cammed engagement with said driving cam on said advancing member; means normally positioning said stop latch into stopping engagement with said 35 drum stop members; indicating means for said drum comprising a pivoted indicator member and a finger adapted to ride against the said drum and webbing carried thereby, and pivoted for movement radially thereto responsive to changing aggregate 40 diameter of webbing and drum to position said indicator.

MYER GENSBURG.
